DIRECTIONS FOR USE To fire the signal tier off the strip of tape that fastens the lid to the box, and apply a piece of lighted match rope (as it makes no light). When it is necessary to make a number composed of more than one figure the six is lighted 7 6 after the other in succession, but in all cases the first must burn out before another is lighted, so instance in the six is lighted as soon as seven is burnt out if after having made the foregoing number, or any other, a second is required, an interval of at least one minute is necessary between the signals. The large red light marked P is intended to call the attention of a squadron to the ship about to make signals as it burns three times as long as No. 2 light which is of the same colour) the difference is easily distinguished.

right having made signal signifying she is understood.

N.B. The signals must be kept in some convenient dry place on deck, for instance, in the signal locker. Do not use any paper or cloth to wrap them in, as they will be ruined by water. 1 2 3 4 5 6 7 8 9 10 11 12 13 14 15 16 17 18 UNITED STATES PATENT OFFICE.

MARTHA J. COSTON, ADMINISTRATRIX OF B. FRANKLIN COSTON, OF WASHINGTON, DISTRICT OF COLUMBIA.

PYROTECHNIC NIGHT-SIGNALS.

Specification of Letters Patent No. 23,536, dated April 5, 1859.

To all whom it may concern:

Be it known that B. FRANKLIN COSTON, late of the city and county of Washington and District of Columbia, deceased, was the original and first inventor of a Method of Signalizing Any Numeral or Combination of Numerals by the Display of Different Pyrotechnic Fires, and that the following is a full and exact description thereof, reference being had to the accompanying sheets of drawings making a part of this specification.

By the aforesaid method or system of signalizing, expression is given to any numeral, or character, by the separate or successive exhibitions of fires of three different colors, viz, red, white and blue. The pyrotechnic materials for producing, by their combustion, fires of the above mentioned colors, are put up in strong paper boxes of three different sizes, viz, a size which will contain the material for a single signal-fire of short duration; a size which will contain the materials for producing in succession, two of the aforesaid signal-fires; and a size which will contain the materials for producing in succession the three signal-fires employed in the COSTON system of displaying signals.

The shape and size of each of the above mentioned boxes are clearly represented by Figures 1, 2, and 3, of Sheet 1; and the other drawings on said sheet represent the style of indicative labels that are generally placed upon the said boxes. Sheet 2, is a chart containing the necessary illustrations and directions for using the COSTON system of night signals.

After receiving their respective charges of pyrotechnic composition, the aforesaid boxes may be rendered water-proof by first pasting a piece of tape (b) over the joint between the cover and the body of each box, and then coating the boxes with varnish, or any other suitable water-proof composition.

For the purpose of enabling the joint-covering piece of tape to be readily taken hold of and stripped from a box, preparatory to removing the cover therefrom and applying fire to its contents, one end of said tape should be left unconfined—as represented by the drawings on Sheet 1.

By the aforesaid system of making signals the different numerals and the other enumerated communications, are expressed in the following manner, viz.—a single white fire, of short duration, indicates No. 1; a single red fire, of short duration, indicates No. 2; a single blue fire, of short duration, indicates No. 3; a white fire running into a red fire, indicates No. 4; a white fire running into a blue fire, indicates No. 5; a red fire running into a white fire, indicates No. 6; a red fire running into a blue fire, indicates No. 7; a blue fire running into a white fire, indicates No. 8; a blue fire running into a red fire, indicates No. 9; a white fire running into a red fire and the latter running into a blue fire, indicates the character 0. 60

A prolonged white fire—produced by burning the contents of the case marked P—indicates that the vessel or person exhibiting said signal, is desirous to communicate with some other vessel or person by means of the COSTON signals: and a prolonged red fire—produced by burning the contents of the box marked A,—is the answer to the aforesaid signal, expressing a readiness to answer signal by signal.

Directions for use.—To fire a signal, strip off the tape from a box, remove the cover and apply a lighted match-rope to the contents of the box. The boxes which are necessary to express a signal composed of a combination of two, three, or more numerals, should be fired one after the other in quite rapid succession; and then an interval of something like the space of a minute, should be allowed to elapse before firing the first 85

It is doubtless well known at the Patent Office, that signal books containing an almost infinite variety of numbered sentences have been published and are now generally used on public and private vessels, but prior to the invention of the COSTON system of making night-signals, the said signal-books could only be used during the hours of the day.

That which it is desired to secure by Letters Patent as the invention of the late B. FRANKLIN COSTON, is

The signalizing of any numeral, combination of numerals, or any character or combination of characters, by a methodical exhibition of different pyrotechnic fires, substantially as herein set forth.
